CLAIM

The ornamental design for a laptop stand, as shown and described.

DESCRIPTION

FIG. 1 is a front, right, and top perspective view of a laptop stand, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a bracket; and,

FIG. 10 is a partial enlarged view of an area labeled 10 in FIG. 2 showing a screw cap.

The dash-dash broken lines shown in the drawings are included for the purpose of illustrating portions of the laptop stand that form no part of the claimed design. The dot-dash broken lines shown in the drawings are included for the purpose of illustrating the boundaries of the partial enlarged views and form no part of the claimed design.

1 Claim, 10 Drawing Sheets
